Term of patent 14 years

(Cl. D87—3)

FIGURE 1 is a perspective view of a photograph album, the album being in the open condition, showing my new design.

My design comprises a photograph album consisting of three sets of individual wallets arranged in spaced-apart relationship between the covers; each set of wallets is retained by an individual set of rings; the set of rings also being in spaced-apart relationship and secured to a backing member.

I claim:

The ornamental design for a photograph album, substantially as shown and described.
